UNITED STATES PATENT OFFICE.

JOHN HUBER, OF WILMINGTON, DELAWARE.

FLANGING APPARATUS.

Application filed July 12, 1923. Serial No. 651,088.

The invention relates to apparatus for flanging hollow sheet-metal articles such as tanks, boilers, tubes, shells and the like, and, generally stated, involves an improved construction of flanging means capable of being readily attached to an organized power actuating mechanism such, for example, as a punch, press, or shear machine.

The object of the present invention is to provide a flanging apparatus including in combination means for supporting and centering the hollow cylinder-like articles upon a work support, said means acting to yieldingly support the work, and flanging means adapted to form either an internal or an external flange upon the ends of the work, said flanging means comprising co-acting metal bending dies one of which is relatively stationary and the other of which is adapted to be successively positioned and moved a predetermined distance after each positioning for bending the edge of the article to progressively form the flange.

A further object of the invention resides in the provision of co-acting pressing dies, one of which is designed to remain relatively fixed during the pressing operation and the other of which is movable through a predetermined path of travel, said movable die being detachably connected with the reciprocating plunger or moving part of the organized mechanism, means being provided between said plunger and movable die for progressively positioning the same to effect the succeeding bending operation, said means involving a plurality of differently sized detachable supporting members of strong and reliable construction.

The invention further consists in the combination, arrangement and construction of the several parts associated with an operating mechanism to provide a rapid and economical flanging apparatus capable of forming very deep flanges upon either the inside or outside of sleeve-like structures such as the cylindrical portions of boilers and tanks.

In the drawings illustrating two embodiments of the invention used respectively for forming internal and external flanges:

Figure 1 is a view in side elevation of a fragmentary portion of a power punch showing my improved apparatus associated therewith, the cylindrical work being shown in longitudinal section.

Fig. 2 is a top plan view of the apparatus shown in Fig. 1 with the work removed, the

movable pressing die being shown in horizontal section.

Fig. 3 is a detail transverse sectional view through one of the yieldable supporting means showing the work supported thereon in dot and dash lines.

Fig. 4 is a vertical transverse sectional view on the line 4—4 of Figure 1.

Figs. 5, 6 and 7 are detail views in sectional elevation illustrating the successive positions of the co-acting bending dies, the movable die being shown in its successively lowered position through the interpositioning of the detachable die supporting blocks.

Fig. 8 is a detail front elevation of the movable die in its lowermost position as shown in Fig. 7, the work supporting frame being shown in transverse section.

Fig. 9 is a detail transverse sectional view on the line 9—9 of Fig. 1, viewed in the direction of the arrows.

Fig. 10 is a view in side elevation with parts broken away and illustrating an embodiment of my invention adapted to form external or outside flanges upon the work.

Referring to the drawings in which similar reference characters designate corresponding parts in the several views, I have shown in Fig. 1 a portion of an organized mechanism such for example as a power punch, shear or press having the usual supporting base and head from which latter projects the reciprocating plunger 1 operated in any suitable manner. The work support 2 is adapted to be connected to the supporting base of the machine by means of bolts 3, said work support projecting from the base and disposed at an inclination, as shown. The work support is preferably in the form of a casting having the web or bed portion 4 from which depend suitable webs 5. The bed 4 is continued across the upper portion of the base of the machine and has depending therefrom flanges 5 through which pass the bolts 3 which firmly connect the work support to the machine.

The article to be flanged is indicated by the numeral 6, said article being supported by yieldable means provided on the work support. The yieldable supporting means includes a plurality of longitudinally and transversely arranged supporting rollers 7, each of said rollers being freely mounted at the upper end of a slidable bar 8 which bar is yieldingly mounted within a suitable casing 9. A spring 10 is interposed between the bottom of the bar 8 and a suitable follower 11

adjustably movable with respect to the bottom of the casing. An adjusting screw 12 serves to regulate the compression of the spring. Provided in each of the sliding bars 8 is an elongated opening or slot 13 through which extends a pin 14 which latter also passes through the walls of the casing 9, said pin and slot connection serving to maintain the roller with its shaft disposed parallel to the axis of the cylindrical article being flanged and prevent any turning tendency of the bar 8 within the casing 9. As shown in Fig. 3, the article is supported upon the rollers 7 at each side of the work support, said rollers being shown in their lowermost position.

The supporting rollers are preferably arranged in pairs transversely of the axis of the cylindrical work being flanged, the respective casings 9 of each roller being united by a cross plate 15, the opposite ends of which are inclined downwardly, as shown in Fig. 3, for receiving the casings and sliding bars therein at substantially right angles to the inclined ends. The connecting plate 15 is slidably mounted upon the bed portion 4 of the work support, the outstanding flanges 16 of said support being received within suitable guideway 17 formed on the said connecting member 15. A suitable block 18 and attached plate 19, which latter underlies the adjacent projecting portion 16 at each side, are connected to the plate 15 and form the guideway to permit of the longitudinal adjustment of the supporting rollers according to the length of the article being flanged. I have shown two groups of supporting rollers 7 but it will be understood that in some cases a greater or less number may be employed.

The arrangement of the supporting rollers 7 upon opposite sides of that portion of the article which is subjected to a flanging operation, provides for the uniform support of the article and centering thereof with respect to the pressing dies. In addition, it will be seen that the article can be easily rotated to bring the adjacent portion hereof which is to be subjected to the flanging operation, into position.

The article is adapted to be maintained in position with respect to the anvil 20 projecting upwardly from the work support, by means of a longitudinally movable member 21, said member being slidably mounted upon the work support and having a projecting portion 22 adapted to overlie the exterior of the article and limit any upward movement thereof incident to the flanging operation. The projecting portion 22 is in the form of a plate suitably secured to a cross plate 23, said cross plate being provided with depending and underlying flanges 24 which provide guideways into which the projecting portions 16 of the bed of the support extend, as

best shown in Fig. 9. The end of the work is adapted to lie against the upstanding portion of the member 22, said member being located so as to position the opposite end of the article with a projecting edge extending beyond the anvil 20 and of a length corresponding to the depth of the flange to be formed. 70

The pressing means for forming the internal flange upon the article, such as illustrated in Fig. 1, involves co-acting die members 25 and 26, the former being associated with the anvil 20 and maintained relatively stationary with respect to the work support, and the latter being movably associated with the reciprocating plunger 1 of the machine. The 75 respective die members are provided with co-acting pressing faces, said faces being disposed substantially parallel to each other and arranged at an angle to the body portion of the article being flanged corresponding to 80 the angle which the finished flange is to have with respect to the article. A plurality of liners 27 may be utilized to properly position the relatively fixed die member 25 with respect to the anvil 20. The die member 25 is 85 also preferably formed with a rounded upper surface to receive the curved portions of the articles being flanged, although it will be understood that said die member may have a different contour commensurate with the 90 shape of the article to be flanged.

The movable die member 26 is adapted to have a predetermined path of travel, the same being preferably that of the distance which the reciprocating plunger of the machine moves. The die member 26 is adapted to impart a plurality of bending operations to the edge of the article, said bending operations being imparted by progressively positioning said die at varying heights with respect to the constant or predetermined path of travel of the reciprocating plunger. 100

The movable die member 26 is detachably connected and progressively positioned with respect to the reciprocating plunger by means of a plurality of differently sized supporting members, each of which is formed with a dove-tail connection 28 for connection to the reciprocating plunger 1, and a dove-tail connection 29 for supporting the die. The supporting member or block first used for holding the die 26 when imparting the initial bend to the edge of the article, is indicated by the numeral 30. The supporting block next used for detachably connecting the die member to the plunger for giving the next bend to the edge of the work is indicated by the numeral 31, and the block member finally used to complete the formation of the flange is designated by the numeral 32. In the construction shown, it will be obvious that the successively used die supporting blocks can be readily inserted in the reciprocating plunger and rapidly detached, the movable die being also rapidly inserted and removed. 110 115 120 125 130

The movable die member is retained in vertical alinement by means of guide brackets 33, said brackets being connected to an upright web 34 of the work support, by means of the bolts 35. Each bracket is formed with an inwardly inclined wall 36, the walls of the brackets forming, together with the upright 34, a dove-tail guideway in which the movable pressing die reciprocates.

In operation the work or article to be flanged is supported from the interior by means of the rollers 7, the holding member, and more especially the projecting portion 22 thereof, being brought into engagement with the lower end of the article after the upper end thereof has been positioned with respect to the size of the flange to be formed by the bending dies. Movement of the reciprocating plunger 1 in a downward direction causes the projecting edge of the article to be bent between the co-acting die members, as shown in Fig. 5. The plunger is then moved upwardly and the detachable supporting block 30 removed and the next sized supporting block 31 inserted, the same die member being preferably connected to the substituted supporting block 31. The increase in depth of the supporting block 31 is sufficient to provide for the succeeding bending operation in forming the flange to the position shown in Fig. 6. The final bending of the edge to form the flange occurs when the largest supporting block 32 is inserted in the reciprocating plunger with the die member connected thereto, the latter being caused to move downwardly when the machine is operated to form the finished flange, as shown in Fig. 7. In each of the successive operations the same movable die member may be used, although in some cases it may be found desirable to utilize die members of varying lengths which, when successively used, will produce the same progressive bending of the work to form the flange. This latter construction of die member is set forth in my co-pending application bearing Serial No. 651,087 filed as of even date herewith.

In Fig. 10 of the drawings an embodiment of my invention is disclosed in which the article 37 is supported upon the exterior thereof by means of rollers 7^a, the flange to be formed being an outside or exterior one, as shown. The same arrangement of relatively fixed and co-acting members is utilized and the substitution of varying sized supporting members for the movable die is effected. In all other respects the adaptation of my invention to form outside flanges upon curved or cylinder-like objects of a hollow metallic nature is the same and a detailed description thereof will not be given.

A machine constructed in accordance with my present invention provides a comparatively simple apparatus in which relatively deep flanges can be produced without strain-

ing the punch or buckling the material, it being obvious that the yielding character of the supporting rollers permits their remaining in contact with the article between the point of bending and the relatively remote point at which the article is held from the exterior. It will also be observed that the several parts can be inexpensively constructed and comparatively large quantities of articles flanged in a minimum amount of time.

What is claimed is:

1. The combination with an organized machine having a reciprocating plunger, of a work support, means for supporting and centering the work upon said support, means for pressing the edge of the work to form a flange, said means including a pair of co-acting bending dies one of which is adapted to be maintained relatively stationary and the other of which is adapted to be moved through a predetermined distance, and means including a supporting member replaceable by another supporting member of a different size for detachably connecting the movable die to the reciprocating plunger to gradually bend the work to the desired extent.

2. The combination with an organized machine having a reciprocating plunger, of a work support, means for supporting and centering the work upon said support, a pair of co-acting bending dies one of which is relatively fixed and the other of which is adapted to be moved through a predetermined and constant path of travel, and means for detachably connecting said movable die to the reciprocating plunger for successively positioning said die closer to the work to progressively bend the edge of the work to form a flange.

3. In an organized mechanism for flanging hollow cylinder-like articles, the combination with a reciprocating plunger, of a work support, an anvil, means provided on said work support for yieldingly sustaining the work with the portion to be flanged associated with said anvil, a pair of co-acting pressing dies one of which is associated with said anvil and maintained relatively fixed and the other of which is adapted to be moved, and means including a movable die supporting member adapted to detachably connect and position said movable die with respect to the plunger and replaceable by another supporting member of a different size for progressively bending the edge of the material to form the flange.

4. In an organized mechanism for flanging hollow cylinder-like articles, the combination with a reciprocating plunger, of a work support, an anvil, means for yieldingly supporting the work from the interior thereof, a pair of co-acting pressing dies for forming the flange upon the supported work, one of said dies being positioned adjacent the said anvil, and the other of said dies being movable with

relation thereto, and means for positioning said movable die for progressively bending the edge of the work to form the flange.

5. In an organized mechanism for flanging hollow articles such as cylinders, tubular sleeves and the like, the combination with a movable member having a predetermined path of travel, of a work support, a relatively stationary die mounted on said work support and having a face disposed at the angle which the flange to be formed is to bear to the work, a movable coacting die having a pressing face disposed in parallel relation to the face upon said first named die, and means for detachably connecting and changing the relative position of said movable die with respect to the aforesaid movable member for progressively bending the work to form a relatively deep flange.
- 20 6. In an organized mechanism for flanging hollow articles of a curved and cylinder-like nature, the combination with a reciprocating plunger, of a work support, a pair of co-acting pressing dies for bending the edge 25 of the material to form a flange, one of said dies being mounted upon the work support in relatively fixed relation and the other of said dies being movable with respect thereto, and means for detachably supporting said 30 movable die from the plunger at a series of varying heights for progressively bending the edge of the work to form a relatively deep flange.
- 35 7. In an organized mechanism for flanging hollow articles of a curved and cylinder-like nature, the combination with a reciprocating plunger, of a work support, a pair of co-acting pressing dies for bending the edge of the material to form a flange, one of said dies 40 being mounted upon the work support in relatively fixed relation and the other of said dies being movable with respect thereto, and means including a supporting member adapted to detachably connect and support the 45 said movable die with relation to the plunger and replaceable by another supporting member of a different size whereby said die is adapted to progressively bend the work to form a relatively deep flange.
- 50 8. In an organized mechanism for flanging hollow metal articles, the combination with a reciprocating plunger, of an anvil having a relatively stationary die portion over which the edge of the article is bent, means including a plurality of longitudinally and transversely arranged members adapted to support the article, said means acting to center the article upon said anvil, means for holding the article upon said anvil with a portion 55 thereof projecting beyond the edge of the anvil a distance corresponding to the size of the flange to be formed, and means for pressing the edge of the article over the anvil.
- 60 9. In an organized mechanism for flanging hollow metal articles, the combination with 65

a reciprocating plunger, of an anvil having a relatively stationary die portion over which the edge of the article is bent, means including a plurality of longitudinally and transversely arranged members adapted to support the article, means acting to center the article upon said anvil, means for holding the article upon said anvil with a portion thereof projecting beyond the edge of the anvil a distance corresponding to the size of the flange to be formed, means for bending said projecting edge over the anvil, and means for detachably supporting said last named means at a series of varying heights to effect a progressive bending of the flange.

70 10. In an organized mechanism adapted to form flanges upon hollow metal articles, the combination with a movable member having a relatively constant stroke, of a work support and relatively fixed die member associated therewith, a co-acting movable die member adapted to bend the edge of the article against said relatively fixed die member, and means independent of the relatively fixed die member for yieldingly supporting said work during the bending operation.

75 11. In an organized mechanism adapted to form flanges upon hollow metal articles, the combination with a movable member having a relatively constant stroke, of a work support and relatively fixed die member associated therewith, a co-acting movable die member adapted to press the edge of the article against said relatively fixed die member, and spring means arranged to support the work from the interior thereof during the pressing operation, said means being disposed upon each side of the longitudinal center line of the work support.

80 12. In an organized mechanism adapted to form flanges upon hollow metal articles, the combination with a movable member having a relatively constant stroke, of a work support and relatively fixed die member associated therewith, a co-acting movable die member adapted to press the edge of the article against said relatively fixed die member, means for yieldingly supporting the work from the interior thereof, said means being disposed axially of the work and adapted to center the same between the co-acting die members, and means for limiting the movement of the work away from the yieldable supporting means during the bending operation.

85 13. In an organized mechanism for flanging hollow cylindrical articles, the combination with a reciprocating plunger, of a work support and relatively fixed die member associated therewith, a movable co-acting die member adapted to press an edge of the article against the first named die member, means for holding the article with a projecting portion of a length corresponding to the depth of the flange to be formed, said

projecting portion being disposed between the co-acting die members, and means for yieldingly supporting the article at a point between the aforesaid holding means and the 5 co-acting die members.

14. In an organized mechanism for flanging hollow cylindrical articles, the combination with a reciprocating plunger through which the power required for the flanging 10 operating is transmitted, of a work support and a relatively fixed die member associated therewith, a movable co-acting die member adapted to press an edge of the article against the first named die member, means for holding 15 the article with a projecting portion of a length corresponding to the depth of the flange to be formed, said projecting portion being disposed between the co-acting die members, and means for holding the article

in substantially its normal supported position, said last named means being located at a point remote from the co-acting die members. 20

15. The combination with an organized machine of the class described having a 25 frame, of a work supporting member attached thereto, a relatively fixed die member connected to said work supporting member at one end thereof, a reciprocating plunger through which the operating power 30 is transmitted, a movable co-acting die member, and means including a plurality of adjustable supports for engaging and holding the work between the die members, said adjustable supports being longitudinally movable upon the work supporting member. 35

In testimony whereof I affix my signature.

JOHN HUBER.
